UNITED STATES PATENT OFFICE.

WILLIAM F. PIERSON, OF GRAND ISLAND, NEBRASKA.

WINDOW-SASH HOLDER.

Application filed March 17, 1928. Serial No. 262,340.

This invention relates to devices for holding window sashes in adjusted position and against accidental movement in either direction after having been adjusted.

5 The general object of the invention is to provide a device of this character which may be inserted in a mortise in the sash which is, therefore, concealed within the mortise, which is not held by screws or like devices 10 which are liable to tear out of place but is supported firmly in position and which will hold the window sash in adjusted position;

15 My invention is illustrated in the accompanying drawings, wherein:—

15 Figure 1 is a fragmentary front elevation of a window sash having a locking device therein constructed in accordance with my invention;

20 Figure 2 is an edge elevation of the window sash;

Figure 3 is a section on the line 3—3 of Figure 2;

25 Figure 4 is a transverse section through the window sash and casing.

25 Referring to the drawing, A designates the window sash and B jambs of the window casing. The sash A has a mortise *a* formed in one rail thereof or in opposite rails as desired and disposed within this mortise is 30 an approximately rectangular casing 10 which supports a transverse shaft 11.

35 Upon this shaft is mounted a roller or equivalent circular member 12 which has one face thereof at 13 somewhat flattened, that is, this side of the circular member is of shorter radius than the remainder of the circular member. The shaft 11 is provided with the operating handle 14 whereby the roller 12 may be manually shifted. When 40 the roller 13 is in the position shown in Figure 3, the window may be moved up or down easily in the ordinary manner, but when this roller 13 is turned by means of the handle 14, it will jam against the window casing, forcing the window sash against the other casing on the opposite side, and the sash will be locked in its adjusted position. It will be seen that with this construction, the weight of the window will tend to urge 45 the roller into tight frictional engagement with the window jamb and thus lock the window against any downward movement.

50 It will be noted in Figure 3 that the casing 10 has disposed within it a curved strip 55 15 of slightly resilient material attached at its lower end to the casing and extending up-

ward and forward over and above the roller and bearing slightly against the roller by virtue of its elasticity. This strip acts to impede a rotation of the roller from the 60 dotted line position in Figure 3 to the full line position in this figure, or in other words when the roller 12 is turned to the full line position in Figure 3 it bears tightly against this spring 15 but when it is turned in either direction slightly beyond this full line position as, for instance, to the dotted line position in Figure 3, the roller moves away 65 from the spring.

Under these circumstances, the roller is 70 held slightly projecting beyond the margin of the window sash so that it will immediately catch and engage the window casing when the sash is urged downward, as by the action of gravity. Of course, by manually turning the roller from the dotted line position to the full line position, the roller will be engaged by this spring and, therefore, held against movement in either direction and is thus rendered inoperative to 75 permit the sash to be raised or lowered without impediment. When the roller is turned opposite to the dotted line position in Figure 3, it will, of course, impede the upward movement of the sash or prevent 80 this upward movement. When it is turned to the dotted line position in Figure 3, it prevents the downward movement of the sash after an upward movement, and when the roller is turned to the full line position 85 it is inoperative and will not work to impede the movement of the sash in either direction. This wheel or roller may be made of metal or of wood, and while I have illustrated a roller or wheel, I do not wish to 90 be limited to this as a ball may be used in place of the wheel.

95 I claim:—

1. A window sash holder of the character described comprising a casing adapted to be 100 inserted into a mortise in the window sash, the casing having therein a roller, one face of which is flattened whereby the roller will 105 exert a camming action against the window frame, a shaft extending through the casing and engaging the roller, the shaft being adapted to be disposed through the face of a window sash into said casing and the roller having a holding means comprising a 110 curved resilient strip attached to the interior of the casing and extending downward beneath said roller and having its end adapted

to engage the end wall of the mortise in which the casing is disposed.

2. A window sash holder of the character described comprising a casing adapted to be inserted into a mortise in the window sash, the casing having therein a roller, one face of which is flattened, a shaft extending through the casing and engaging the roller and extending through the face of the window sash whereby the roller may be manually shifted from a position with its flat

face opposed to the window sash to a position where the longer axis of the roller is slightly oblique to the edge of the window sash, and yielding means for holding the roller in its oblique position and resisting a movement of the roller into a position where its longer axis is parallel to the edge of the window sash. 15

In testimony whereof I hereunto affix my 20
signature.

WILLIAM F. PIERSON.
